UNITED STATES PATENT OFFICE.

CLAUDE E. COX, OF DETROIT, MICHIGAN.

OIL-CUP.

1,400,804.

Specification of Letters Patent. Patented Dec. 20, 1921.

Application filed January 29, 1921. Serial No. 441,027.

To all whom it may concern:

Be it known that I, CLAUDE E. Cox, a citizen of the United States, residing at Detroit, in the county of Wayne and State of Michigan, have invented certain new and useful Improvements in Oil-Cups, of which the following is a specification.

My invention relates to improvements in oil cups and has for its object to provide 10 a cup having a novel and advantageous closure-cap.

In the drawings Figure 1 is a side elevation showing the oil cup, with its cap in closed position in full lines and in open position in dotted lines; Fig. 2 is a central vertical section; and Fig. 3 is a plan view with parts broken away.

The oil cup body or base 10 may be of any suitable construction, generally cylindrical, 20 to provide an oil chamber 11 from which a duct 12 leads through the usual threaded attaching-stem, the construction shown being one in which a central stand-pipe 13 connects with said duct and extends nearly 25 to the top of the chamber. This stand-pipe is shown as surrounded by a slidable sleeve 14 normally extending above the upper end of the pipe and above the oil level, this sleeve being weighted as at 15 30 and suspended on a light spring 16 for vertical vibration to feed oil to the central duct as a result of vibration of the cup. With the details of the functioning of this automatic feed apparatus the present invention 35 is not concerned, save for the facts that it advantageously provides a vertical central duct extending above the normal oil level and open as at 17 at its top, and that it is sometimes desirable to prime the standpipe 40 with oil from a can.

Onto the upper portion of the body is screwed a cover or head 18 formed, above its threaded cylindrical rim 18', into a low or rather long-radius parti-cylindrical dome 45 19, circular in plan and having one or more apertures therein, these preferably being a central aperture 20 alining with the opening 17 of the stand-pipe for pipe-priming and other apertures 21 between the center and 50 cylinder rim of the dome. Upon the spherical surface of the dome fits a parti-spherical sheet-metal cap 22, substantially conforming in size and shape to the dome and radially pivoted, between the edge of the cap and 55 its center, to the head, as by a double-headed

stud 23. The stud is maintained snug in all positions of the cap by a spring washer 24 between the lower stud-head and the under side of the dome, and the cap preferably has made therein, normally to register with one of the apertures in the dome, a latching depression 25. In most instances I prefer to curve the cap on a radius slightly shorter than the radius of the cover-dome (as shown in Fig. 2) so as to accentuate 65 edge-sealing of the cap, lift its center slightly, and give its edge a slight scraping effect when moved over the dome.

Normally the cap stands firmly latched as shown in full lines in Figs. 1 and 2, with 70 its central depression 25 engaging the central hole 20 of the dome, but by applying side-pressure the parti-spherical cap may be swinging around on its radially-extending pivot 23, the latching depression 25 springing out of its hole 20 against the tension of the cap-metal and of the spring washer 24 and, since the sides of the cylinder do not interfere with its movement, the cap may be completely or partially rotated upon its 75 pivot at will, thereby exposing one or all of the outer holes 21 and also the central hole 20 if desired. By virtue of its strength due to curvature, its close sealing of the margins of the dome and its wiping contact with the dome when moved, this form of a cap is particularly desirable for oil-cups subjected to the ravages of fine dust, as those used on automobiles, in mill machinery and the like. Also, it will be noted, 80 the oil cup may be used in very restricted spaces because when fully opened the cap takes up very little lateral space.

I claim:

1. An oil cup having a parti-spherical dome provided with an oil opening, and a parti-spherical cap pivoted, between its center and edge, to the dome.

2. An oil cup having a parti-spherical dome, circular in plan, provided with an oil opening, and a parti-spherical cap of similar plan area, radially pivoted to said cap eccentrically to its circular margin.

3. An oil cup having a parti-spherical dome having an opening therethrough, and a cap also parti-spherical but of slightly smaller radius, pivoted near one edge to the dome.

4. In an oil cup, a head having a parti-spherical dome, with an opening there-

through, and a parti-spherical cap riveted near one edge to the dome and having a depression to engage the dome opening.

5. An oil cup comprising a parti-spherical dome having an opening therethrough, a parti-spherical cap, a pivot wherein said cap is mounted near its edge to swing over or mainly off of the dome, and resilient means for tensioning the pivot.

10 6. The combination with an oil cup body

having an internal standpipe rising above normal oil level, a spherically-domed head having an opening alining with said standpipe and another opening between the pipe-axis and the body-wall, and a parti-spherical cap pivoted to the dome at a point spaced from said openings to permit the cap to pivotally swing over, or away from, said openings. 15
